MACHINE FOR OPERATING UPON SHEET MATERIAL

Joseph Gouldbourn, Leicester, England, assignor to United Shoe Machinery Corporation, Paterson, N. J., a corporation of New Jersey

Application June 30, 1938, Serial No. 216,829
In Great Britain August 19, 1937

4 Claims. (Cl. 164—23)

This invention relates to machines for operating upon sheet material and is herein illustrated as embodied in a clicking machine of the type illustrated in United States Letters Patent No. 921,503, granted May 11, 1909, upon an application filed in the name of Arthur Bates.

Machines of the type referred to commonly comprise a cutting bed, a post, and a presser arm or beam secured to the post and movable about the axis of the post over the cutting bed, there being means for reciprocating the post in the direction of its axis to produce pressure-applying strokes of the pressure arm against a freely movable die thereby forcing the die through sheet material, such as leather, positioned upon the cutting block. During operation of a machine of the type referred to, the cutting bed on the one hand and the presser arm and the frame portion of the machine supporting it on the other, are subject to comparatively great stresses, resulting in a springing action between the presser arm and the cutting bed.

In view of the foregoing, it is an object of the present invention to provide an improved clicking machine in which any springing action between the presser arm and the cutting bed is substantially minimized if not completely eliminated.

In accordance with an important feature of the invention, therefore, the upwardly extending frame portion of a clicking machine of the type referred to, which is provided with bearings for the post carrying the presser arm, is connected by braces to the support for the cutting bed. The braces extend on opposite sides of the machine between the bed support and the upwardly extending frame portion, the braces each comprising a tensioned tie rod having its opposite ends anchored respectively to the bed and to the frame portion.

Other objects of the invention and features of construction will be apparent from the following description and will be pointed out in the claims.

45 In the drawings:

Fig. 1 is a view in side elevation of a clicking machine illustrating a preferred embodiment of the invention;

50 Fig. 2 is a sectional view of the machine taken on the line II—II of Fig. 1; and

Fig. 3 is a sectional view of a bracing member used in the illustrated machine.

Referring to Fig. 1, the illustrated clicking machine comprises a C-shaped frame member 10 containing bearings for the upper and lower

ends of a vertical column or post 12 which may be rotated manually so as to bring a presser arm or beam 14 fixed to the post into any desired position over a cutting block or cutting bed 16. The beam 14 together with the post 12 is reciprocated vertically by mechanism of the nature described in the aforementioned United States Letters Patent No. 921,503, actuated by a belt driven pulley and clutch indicated in Fig. 1 by dotted lines at 18, a handle which moves with the beam 14 being employed to trip the clutch. The cutting block 16 is seated on a casting 22 which is secured by bolts 23 to the lower vertical face of the machine frame 10, there being also a horizontal tongue and groove joint in the 15 abutting faces of the frame member 10 and the casting 22 so as to prevent a downward movement of the casting 22 when cutting blows are delivered by the beam 14. The construction as thus far described is well-known in the art. 20

In order to eliminate or minimize springing action between the beam 14 and the cutting block 16 which has been found regularly to occur in machines of the type under consideration, there are provided struts or braces connecting the 25 upper portion of the machine frame with the casting 22 carrying the cutting block. As illustrated in Figs. 1 and 2, a pair of bars 24 are symmetrically positioned at the sides of the machine frame 10, their upper ends being retained against 30 lugs 26 provided on the machine frame 10 somewhat above the top face of the cutting block 16, the lower ends of the bars 24 being retained against lugs 28 provided at the sides of the casting 22 below the cutting block 16. The bars 24 35 are retained after assembly against the lugs 26 and 28 by nuts 30 threaded on the bar ends which transmit the pressure produced by tensioning the bars 24 through spherically surfaced convex washers 32 to the lugs which have hollow 40 spherical seats to receive the washers 32. A spacer tube 34 is placed around each of the bars 24, each tube being provided with spherical end surfaces arranged to seat in the hollowed sides of collars 36 of which the other and flat sides are 45 seated against the lugs 26 and 28 as may be seen in Fig. 3. Further, as shown in Fig. 3, the holes in the lugs 26 and 28 are made of larger diameter than are the bars 24 giving clearance which insures that the bars 24 will not apply stresses 50 laterally to the lugs 26 and 28 when the nuts 30 are tightened and that all the pressure resulting from such tightening is applied to the hollow surfaces of the lugs through the convex washers 32. Each of the spacer tubes 34 with its collar 55

36 is accurately fitted for length to correspond closely with the distance between the opposing faces of the corresponding lugs 26 and 28 as the machine frame 10 and the casting 22 are set up so that the tightening of the nuts may not put undue stress upon the frame 10 and the casting 22.

In the illustrated machine, as may be seen from Fig. 2, the horizontal angle that each bar 10 28 makes with the line 25 passing through the center of the post 12 and the middle of the top surface of the cutting block 16 is about 35° and, as may be seen from Fig. 1, the vertical angle between the bars 24 and the top surface of the cutting block 16 is about 20°. These angles will, 15 however, be varied in accordance with the width of the cutting block 16 and the horizontal distance between the block and the rear part of the machine frame 10.

Having described my invention, what I claim 20 as new and desire to secure by Letters Patent of the United States is:

1. In a clicking machine having a cutting bed and an upwardly extending frame portion for supporting vertically reciprocable parts including a presser member arranged over the cutting bed, braces extending on opposite sides of the machine between the said bed and said upwardly extending frame portion.
2. In a clicking machine having a cutting bed and an upwardly extending frame portion for supporting vertically reciprocable parts including

5 a presser member arranged over the cutting bed, braces extending on opposite sides of the machine between the said bed and said upwardly extending frame portion, said braces each comprising a tensioned tie rod having its opposite ends anchored respectively to the bed and to said frame portion.

3. In a clicking machine having a cutting bed and an upwardly extending frame portion for supporting vertically reciprocable parts including 10 a presser member arranged over the cutting bed, braces extending on opposite sides of the machine between the said bed and said upwardly extending frame portion, said braces each comprising a tensioned tie rod having its opposite ends anchored respectively to the bed and to said frame portion, and a tubular strut surrounding each tie rod and having its opposite ends connected in abutting relation to the said bed and to said frame portion.

15 4. In a clicking machine having a cutting bed and an upwardly extending frame portion for supporting vertically reciprocable parts including a presser member arranged over the cutting bed, braces extending on opposite sides of the machine 20 between the cutting bed and said upwardly extending frame portion, said braces each comprising a tubular strut having its opposite ends connected in abutting relation to the said bed and to said frame portion.

JOSEPH GOULDBOURN.
